UNITED STATES PATENT OFFICE.

FRANK J. MACDONALD, OF AKRON, OHIO, ASSIGNOR TO THE B. F. GOODRICH COMPANY, OF NEW YORK, N. Y., A CORPORATION OF NEW YORK.

METHOD AND APPARATUS FOR PRESSING LAMINATED MATERIAL.

Application filed March 27, 1922. Serial No. 547,133.

To all whom it may concern:

Be it known that I, FRANK J. MACDONALD, a citizen of the United States, residing at Akron, in the county of Summit and State 5 of Ohio, have invented a certain new and useful Method and Apparatus for Pressing Laminated Material, of which the following is a specification.

This invention relates to the art of making laminated structures, and more particularly for pressing pieces of sheet material, such as parts of rubber-shoe quarters made out of frictioned fabric, upon a larger sheet, such as a sheet of uncured rubber, to form 10 the outer face of said quarter-making piece. It is desirable to have the fabric piece adhere smoothly to the gum sheet, and the object of my invention is to provide a method and apparatus for rapidly and effectively 15 performing this operation to take the place of the usual hand method of pressing and smoothing the cloth pieces.

Of the accompanying drawings, Fig. 1 is a side elevation of a machine constructed 20 according to my invention.

Fig. 2 is a section on a larger scale showing devices for loosening the gum sheet from the liner on the supply-roll and for stripping it back in case of adhesion to the 25 under side of the liner.

Fig. 3 is a cross-section of the tamping devices, taken on the line 3-3 of Fig. 4.

Fig. 4 is a section on the line 4-4 of Fig. 1.

Fig. 5 is a sectional view of parts shown in Fig. 3, on a larger scale, illustrating the action of the tamping bar.

Fig. 6 is a perspective view of the supply-roll for the gum sheet and liner, with the 40 fabric pieces laid thereon.

In the drawings, 10 is the frame of the machine, at opposite ends of which, in suitable bearings, are mounted shafts 11 and 12 for driving a supply-roll or reel 13 and a 45 take-up roll or reel 14, the shaft 11 being frictionally retarded by a band-brake 15, acting on a drum 16, and the shaft 12 being driven by worm gearing 17 and a train of connections, including shaft 18, gear-box 19, pulley 20, and belt 21, from a pulley 22 on an overhead shaft 23, the latter carrying on its opposite end a stepped pulley 24, driven by a belt 25 from the pulley of an electric motor 26. Each roll or reel 13 50 or 14 is composed of a drum, spokes, and a

central arbor, and the drum is detachably coupled with its driving or braking shaft, as the case may be. In Fig. 4, for example, the arbor 14^a for the drum 14 is shown as mounted at one end in a bearing 14^b on the frame, and at the other end in a socket at the inner end of the shaft 12. A similar arrangement is adopted for supporting the arbor 13^a of the roll 13, and the two rolls are rotatably interlocked with the 60 shafts 11 and 12 by means of dogs 11^a and 12^a on the respective shafts engaging a spoke on each roll.

On the upper part of the frame 10, posterior to the supply roll 13, is loosely journaled a roller 27, over which the sheet of unvulcanized rubber gum 28 is adapted to be led as it is stripped in a loop from the underlying cloth liner or apron 29 before the latter unwinds from the supply roll 70 and carries the gum sheet on through the machine. The roller 27 is formed with right-and-left screw-thread ribbing 30, as seen in Fig. 4, which tends to spread the gum sheet and counteract its tendency to 75 contract by elongation as it passes through the loop. Under the roller 27 is loosely journaled a pair of guide-rollers 31, whose axes form an obtuse angle for further counteracting the contracting tendency of the 80 sheet through their spreading action thereon.

After passing the rollers 31, the gum sheet 28 is returned onto the roll 13 and lies loosely against the liner underneath, the 90 purpose of the described stripping action being to avoid the tendency of the gum to stick to the liner, especially when it has remained in contact therewith for a considerable time or in a warm atmosphere.

The pieces of fabric 32 which are to be pressed against the gum sheet are laid by hand on said sheet on the upper side of the supply-roll 13, just before the sheet and liner unwind from said roll, the pieces being placed in rows across the width of the sheet, as indicated in Fig. 6.

In a posterior position, adjacent and parallel to the guide-rollers 27, is mounted a back-stripping roller 33 having a pulley on one end whereby it is driven through belts 34, 35 and a counter-shaft 36 from a pulley 37 on the overhead shaft 23. Above and posterior to the roller 33 is loosely journaled a guide-roller 138, over which the 100

liner and gum strip pass on their way to the tamping device. The roller 33 is rotated in a direction counter to the travel of the liner, and it tends to strip the gum sheet in the 5 loop away from the under side of the liner, in case the sheet in the loop should tend to follow the back or under side of said liner, as indicated by the broken lines in Fig. 2.

For the purpose of pressing the fabric 10 pieces smoothly upon the sheet of gum 28, it has been attempted to employ a roller or pair of rollers, one above and one below the gum sheet and liner, but it was found that the action of the top roller caused a wave or 15 bank in the gum sheet approaching the nip of the rolls, which was very objectionable. This difficulty I have overcome by the use of an intermittent tamping action which allows the bank effect to disappear or to be 20 absorbed by recoil of the gum sheet between strokes of the tamping device, and I find it especially desirable to employ a tamping tool or instrumentality which has both a motion normal to the feed of the work and 25 a motion parallel and in the same direction therewith, the resultant being a gyratory path of motion of the tamping tool.

30 38 is a work-supporting or anvil roller, over which the work passes, said roller being faced with soft rubber and being idly mounted in bearings at the ends of a pair of horizontal arms 39 which are pivoted on a cross-rod 40 on the frame of the machine, the vertical position of the roller 38 being 35 subject to adjustment by a pair of screws 41 having sprocket-wheels 42 at their lower ends connected by a chain 43, the manipulation of which turns both screws equally one way or the other.

40 Above and parallel with the roller 38 is located a tamping bar 44 formed on the lower ends of a plate or beam 45 which is bolted to a pair of pitmen 46. These pitmen are pivoted on crank-pins 47 turned on the shaft 45 23. The lower ends of the pitmen are guided by pins 48 on the ends of a pair of arms 49, which are pivoted to a cross-bar 50 on the frame.

In the operation of this machine, the cloth 50 liner 29 and gum sheet 28, unwound from the roll 13, are passed over the guide-roller 138 and over the anvil-roller 38, onto the roll 14, and are wound up on the latter by the action of the worm gearing 17 and its driving 55 mechanism propelled by the motor 26. In first setting up a fresh roll 13, a gum sheet is separated from the liner and its leading end is passed over the rollers 27 and 31, while the leading end of the liner is passed 60 under said rollers, so that the gum digresses in a loop, as shown and described, the two being then brought together and carried part way around the roll 13 before being unwound therefrom to pass over the roller 138. The liner is made somewhat longer

than the gum strip and is strung through the machine onto the take-up roll 14, before the gum strip begins to unwind. The machine being then started in motion, the gum sheet 28 is loosened from the liner by passing in a loop over the rollers 27 and 31, as described, and is spread out to counteract its contracting tendency by the helical ribs 30 on the roller 27 and by the divergence of the rollers 31, the reversely-rotated back-stripping roller 33 serving to strip off the gum sheet from the under side of the liner, in case it should cling thereto, as indicated by the broken lines in Fig. 2. The cloth pieces or quarters 32 being placed in rows by hand on the gum sheet, the latter progresses with the liner onto the anvil-roller 38 and is there subjected to a rapid tamping action by the bar 44. Shaft 23 being rotated in the direction of the arrow 51, the crank-pins 47 will impart to the pitmen 46 a combined oscillating and vertical reciprocating motion under the guidance of the arms 49, which will result in a gyratory or revolving movement of the tamping bar 44, the latter while in contact with the work moving in a direction parallel with the feed thereof. In the particular arrangement shown, this path is somewhat elliptical, as represented approximately by the arrow 52 in Fig. 5, and the effect is to press the fabric pieces 32 smoothly against the gum sheet 28, the intermittent action permitting the sheet to recover between the strokes from any draw thereon while the pressure is being exerted. I prefer to have the strokes of the tamping bar come about every quarter of an inch upon the work, but the frequency of their occurrence may be varied, depending upon the ratio between the rate of feed of the work 105 and the rate of rotation of the shaft 23.

The gum strip with the adhering cloth quarters is wound up together with the liner upon the roll 14, and when the roll 13 has been exhausted its drum is transferred to 110 the take-up and a fresh one substituted, the rolled-up drum being removed and the material therein being subsequently unwound and subjected to certain steps of manufacture.

115 It will be understood that my invention is not limited to the described details of construction but may be variously modified within the scope of the claims.

I claim:

1. The herein-described method which comprises imparting a feed movement to laminations of material and pressing said laminations together by a rapid succession of tamping strokes exerted transversely of and in the same direction as the feed of the work.

120 2. In a machine of the character described, the combination of a tamping device, means for imparting thereto a gyra- 125

tory tamping motion, and means for feeding the work past said device.

3. In a machine of the character described, the combination of supply and take-up rolls adapted to feed the work, a tamping device for pressing the work, and means for imparting to said device a gyroscopic tamping movement.

4. In a machine of the character described, the combination of an anvil-roller, a tamping bar coacting therewith, means for imparting to said bar a gyroscopic tamping movement, and means for feeding the work between said roller and bar.

15 5. In a machine of the character described, the combination of an anvil device, a tamping bar coacting therewith, a crank and pitman for reciprocating and oscillating said bar, and an arm for pivotally guiding said pitman.

20 6. In a machine of the character described, the combination of an anvil roller, means for feeding the work thereover, a bar parallel with the axis of said roller for tamping the work against the surface of the roller, and a shaft parallel to said roller and having a series of cranks, pitmen connecting said cranks with the tamping bar, and rocker arms for pivotally guiding said pitmen.

30 7. In a machine of the character described, the combination of means for pressing cloth pieces against a sheet of gum, a roll for supplying said sheet on a liner to the pressing means, and means for leading the gum sheet in a loop away from and back onto the liner on said roll prior to the unwinding of the liner.

40 8. In a machine of the character described, the combination of means for pressing cloth pieces against a sheet of gum, a

roll for supplying said sheet on a liner to the pressing means, and means for leading the gum sheet in a loop away from and back onto the liner on said roll prior to the 45 unwinding of the liner, said means having provision for spreading the gum sheet in passing through the loop.

9. In a machine of the character described, the combination of means for pressing fabric pieces on a sheet of gum, a roll for supplying said sheet on a liner to the pressing means, and a roller structure for looping the gum away from the liner before 50 said liner and the gum sheet unwind from the roll, said roller structure having right-and-left threads for spreading the gum sheet.

10. In a machine of the character described, the combination of means for pressing fabric pieces on a sheet of gum, a roll for supplying said sheet on a liner to the pressing means, and a pair of rollers for looping the gum sheet from the liner before 55 said liner and sheet unwind from the roll, said rollers diverging at an angle to spread the gum sheet.

11. In a machine of the character described, the combination of means for pressing fabric pieces against a sheet of gum, a 60 roller for supplying said sheet on a liner to the pressing means, means for looping the gum sheet away from and back onto the liner before the latter unwinds from said roll, a back-stripping roller adjacent 70 to the looping means, and mechanism for reversely rotating said back-stripping roller.

In witness whereof I have hereunto set my hand this 25 day of March, 1922. 80

FRANK J. MACDONALD.
